UNITED STATES PATENT OFFICE

2,632,641

TILTABLE TRACTION WHEEL FOR FEEDING
STRIP TO ROLLING MILLSDonald E. Rice, Antioch, Calif., assignor to United
States Steel Corporation, a corporation of New
Jersey

Application March 9, 1950, Serial No. 148,529

8 Claims. (Cl. 271—2.4)

1

This invention relates to a rolling-mill accessory and, in particular, to a device for feeding the end of a coil of strip from an uncoiler toward the first stand of a continuous cold-rolling mill.

In the reduction of hot-rolled steel strip to finished gauge by cold-rolling, the pickled strip is delivered to a multistand continuous mill in coils. The end of each coil must be individually started into and threaded through the mill. This consumes a certain amount of time which is unproductive so far as actual output from the mill is concerned. The end of the coil has commonly been fed manually for starting it through the first stand although it is an awkward and cumbersome thing to handle.

In an effort to overcome this disadvantage, a stand of driven pinch rolls has in some cases been installed between the usual uncoiler and the first stand of the mill to feed the strip from the former to the latter. This was an improvement over manual feeding but experience has shown that pinch rolls are not themselves entirely trouble free. In the first place, the pinch roll housings take up considerable floor space adjacent the entry end of the mill and require that the end of the coil be manipulated for entry between the pinch rolls entirely from the front thereof. This handling of the coil end is less difficult only in degree than that involved in feeding the coil end to the mill entirely by hand. Unless carefully adjusted, furthermore, pinch rolls may exert more friction adjacent one edge of the strip than adjacent the other causing skewing and thereby feeding the strip toward the mill on an angle to its center line.

I have invented an improved apparatus for feeding the end of a coil to the first stand of a continuous mill, which overcomes the aforementioned objections and is characterized by several novel features and further advantages. Generally speaking, the invention comprises a traction wheel mounted on a tilting cantilever shaft for cooperation with a supporting roll extending across the path of the strip from the coil to the mill. The shaft is supported at one side of the strip path and is adapted to reach about halfway across it. I provide power means for tilting the shaft and other means for driving it. The supporting roll is fitted with guide collars and means for adjusting them toward and from each other.

A complete understanding of the invention may be obtained from the following detailed description and explanation which refer to the accompanying drawings illustrating a preferred embodiment. In the drawings,

Figure 1 is a view partly in side elevation and

2

partly in section showing the relation of the improved feeding apparatus to the uncoilers and the mill;

Figure 2 is a plan view of the feeding apparatus itself;

Figure 3 is a vertical section taken along the plane of line III—III of Figure 2, showing parts in elevation;

Figure 4 is a horizontal section taken along the plane of line IV—IV of Figure 3; and

Figure 5 is an elevation of the end of the apparatus opposite that shown in Figure 1.

Referring now in detail to the drawings and for the moment to Figure 1, the improved feeding apparatus as there illustrated is applied to a continuous mill, the first stand of which is designated at 10. The feeding apparatus itself is indicated generally at 11. It is mounted on a pair of spaced parallel rails 12 connected by a transverse box-section girder 13 and serves to feed toward the mill the end of a coil disposed in one of two uncoilers 14 and 15.

Referring now more particularly to Figures 2 through 5, a supporting roll 16 comprising a barrel 16^a and end discs 16^b is journaled on a shaft 17 extending between rails 12. Guide collars 18 are splined on the roll 16 for engagement with the edges of the strip to confine it to a predetermined path in traveling from the uncoiler toward the mill, as indicated at 19 in Figure 2. The collars 18 are adjusted by means of shifters 20 adapted to travel along a screw shaft 21 journaled in the rails 12 and in lugs 22 extending from one side wall of the girder 13. The shifters 20 have nuts 23 therein threaded on the shaft and laterally projecting fingers 24 fitting in circumferential grooves 25 in the outer sides of the collars. A handwheel 26 on the screw shaft facilitates manual rotation of the latter for adjustment of the collars to suit the width of the strip being rolled.

A bracket 27 secured to the top of the girder 13 at one end thereof has spaced bearing hubs 28 disposed on a common axis parallel to the path of the strip. A rock shaft 29 journaled in these hubs has a crank arm 30 keyed thereto and extending laterally therefrom. A fluid-pressure cylinder 31 is pivotally mounted on spaced lugs 32 extending downwardly from the hubs 28 and has a piston rod 33 pivoted to the arm 30.

The end of shaft 29 nearer the uncoilers has a head 34 thereon with a bore therethrough parallel to the roll 16. A tubular arm 35 extends through this bore and has a shaft 36 journaled in bearings 37 seated in the ends thereof. As shown, the shaft reaches about the center of the strip path. A traction wheel 38 is secured

to the inner end of the shaft and is provided with a surface layer or tire of friction material 39, e. g., brake lining. The wheel 38 is adapted, when the arm 35 is in the position shown in solid lines in Figure 3, to cooperate with roll 16 for the purpose of feeding strip toward the mill. A motor 40 having built-in reduction gearing is mounted on a bracket 41 carried by the head 34 and drives the shaft 36 through a suitable belt-and-pulley drive 42 as clearly shown in Figures 3 and 5.

The arm 35 is normally tilted upwardly to the position shown in dotted lines in Figure 3 by controlling the supply of motive fluid to the cylinder 31. The traction wheel is thus held out of the way during the actual rolling operation, being lowered only during the starting and threading of the coil through the mill. The operation of cylinder 31 is controlled by a suitable valve and the motor 40 by a switch under the control of the operator whereby tractive effort may be applied to the strip in either direction or released altogether as desired.

In operation, the coil end is placed on the supporting roll 16 while the arm 35 is up-tilted. The arm is then tilted down by the cylinder 31 until the traction roll exerts appropriate pressure on the strip. The motor 40 is then started to advance the strip along its path toward the mill. When properly entered therein, the arm 35 is again tilted up during completion of the threading of the strip through the mill and the actual running of the coil therethrough. While one coil is running, the succeeding coil is placed on its uncoiler and the outer end thereof laid on top of the strip unwinding from the running coil. The arm 35 is then tilted downward so as to exert only sufficient pressure on the end of the second coil to hold it while permitting the strip from the running coil to continue paying out. The second coil can thus be started almost immediately after the inner end of the running coil has entered the mill. In case the leading coil end should be improperly started in the mill it can be backed out by reversing the motor 40.

It will be apparent that the invention possesses a marked advantage over both manual handling of the coil end during starting and the pinch rolls formerly employed. In the first place, the fact that the traction roll is movable to an out-of-the-way position when not actually in operation permits the coil end to be placed on the supporting roll 16 from one side. This clearly facilitates the starting operation as compared to the threading of the coil end between a pair of pinch rolls. In addition, the traction roll exerts its force exactly at the center of the strip. This minimizes the possibility of feeding the strip on a skew instead of precisely along the center line of the mill. In case of failure of the power-feeding mechanism, furthermore, the traction roll being out of the way permits manual feeding of the coil end during the emergency. Finally, the tiltable mounting of the traction wheel permits the placement of a second coil while a previously started coil is running through the mill. This reduces the over-all time required between the finishing of one coil and the starting of the next one.

I claim:

1. Apparatus for feeding the end of a coil of strip along a predetermined path comprising a roll journaled transversely of said path for supporting the strip, an arm pivoted adjacent the path on an axis parallel thereto, a shaft jour-

naled in said arm and extending part way across the path, a traction wheel on said shaft adapted to cooperate with said roll, and means for tilting said arm to lower the wheel toward the roll or raise it therefrom.

2. The apparatus defined by claim 1 characterized by a rock shaft on which said arm is mounted and a crank arm on said rock shaft, said tilting means being connected to said crank arm.

3. The apparatus defined by claim 1 characterized by said means including a fluid-pressure cylinder and piston and a member actuated thereby effective to tilt said arm through a predetermined angle.

4. The apparatus defined by claim 1 characterized by a motor mounted on said arm having driving connection with said shaft.

5. Apparatus for feeding the end of a coil of strip along a predetermined path comprising a pair of spaced parallel rails one on each side of said path, a strip-supporting roll journaled in said rails transversely thereof, a bearing bracket secured to one of said rails, a rock shaft journaled in said bracket parallel to said rails, an arm mounted on said rock shaft extending part way across said path above said roll, a shaft journaled in said arm, a wheel mounted on said last-mentioned shaft for cooperation with said roll and means for oscillating the rock shaft to tilt said arm.

6. Apparatus for feeding the end of a coil of strip along a predetermined path comprising a roll journaled transversely of said path for supporting the strip, a rock shaft parallel to said path journaled adjacent one side thereof, an arm mounted on said rock shaft extending part way across said path above said roll, a shaft journaled in said arm, a wheel mounted on said last-mentioned shaft for cooperation with said roll and means for oscillating the rock shaft to tilt said arm.

7. The apparatus defined by claim 6 characterized by a crank arm on said rock shaft and a fluid-pressure cylinder and piston pivoted to said crank arm.

8. Apparatus for feeding the end of a coil of strip along a predetermined path comprising a roll journaled transversely of said path for supporting the strip, a rock shaft parallel to said path journaled adjacent one side thereof, a second shaft rotatably mounted on said first-mentioned shaft and extending normal thereto part way across said path above said roll, a wheel mounted on said second shaft for cooperation with said roll and means for oscillating the rock shaft to tilt the second shaft and thereby raise said wheel from said roll or lower it thereon.

DONALD E. RICE.
